United States Patent

Des. 235,747
Patented July 8, 1975

235,747

AUDIBLE ALARM

Louis P. Sweany, Carmel, Ind., assignor to P. R. Mallory
& Co. Inc., Indianapolis, Ind.

Filed Aug. 29, 1973, Ser. No. 392,623

Term of patent 14 years

Int. Cl. D29—02

U.S. Cl. D10—120

FIG. 1

FIG. 5

FIG. 2

FIG. 3

FIG. 6

FIG. 4

FIG. 1 is a side elevation view of an audible alarm showing my new design;

FIG. 2 is another side elevation view thereof;

FIG. 3 is a top view thereof;

FIG. 4 is a bottom view thereof;

FIG. 5 is a front elevation view thereof; and

FIG. 6 is a rear elevation view thereof.

The leads are shown in broken lines in FIGS. 1, 2, 3, 4 and 6 for illustrative purposes only.

I claim:

The ornamental design for an audible alarm, substantially as shown and described.
